UNITED STATES PATENT OFFICE.

WALTER DE MATTOS, OF OTTAWA, ONTARIO, CANADA.

MEANS FOR SUPPLYING TEMPORARY TABLE-COVERS.

1,397,800.

Specification of Letters Patent.

Patented Nov. 22, 1921.

Application filed June 24, 1921. Serial No. 480,122.

To all whom it may concern:

Be it known that I, WALTER DE MATTOS, a subject of the King of Great Britain, and resident of the city of Ottawa, in the Province of Ontario and Dominion of Canada, have invented certain new and useful Improvements in Means for Supplying Temporary Table-Covers, of which the following is a specification.

10 This invention relates to improvements in means for supplying temporary table covers, and has for its objects to provide a device by which a paper table cover embossed or otherwise, may be supplied to a table and rapidly removed.

15 Further objects of the invention are to provide means for holding the table cover evenly in position on the top of the table, and such a device as may be of inconspicuous character and not likely to mar or injure the surface of the table.

20 Further objects of the invention are to provide means for supporting the roll of paper from which the table covers are formed and for cutting off the soiled portions from time to time.

25 The invention consists essentially of the improved construction hereinafter described in detail in the accompanying specifications and drawings.

30 In the drawings:

Figure 1 is a perspective view showing the device in position on a table.

35 Fig. 2 is a perspective view of the clamping means.

Fig. 3 is a side view of the clamping means and supporting bracket.

Fig. 4 is a transverse sectional elevation.

40 Fig. 5 is a sectional detail through the clamping bar and cut-off device.

Fig. 6 is a perspective detail of one of the clamps and of the retaining bar.

Fig. 7 is a perspective detail of the supporting bracket for the end of the roller.

45 Fig. 8 is a sectional detail of the support for the roller.

Fig. 9 is a detail showing an alternative form of clamp.

50 Fig. 10 is a detail showing the form of intermediate support for the rollers which may be omitted on short tables.

In the drawings, like characters of reference indicate corresponding parts in all the figures.

55 Referring to the drawings:

A indicates a suitable table. The present

invention is designed to supply a paper table cover either to a table without a linen table-cloth or with a linen table-cloth, thus serving to either protect the linen table cloth or 60 as a substitute therefor. The paper cloth which may be suitably embossed with an ornamental design is made in the form of a continuous roll B supported on a core 10 having end pintles 11 journaled in pivoted 65 end supports 12 mounted on brackets 13 which are connected to the corner of the table by U-shaped clamps 14 designed to fit closely to the upper and lower and end surface of the top board of the table. 70

A spring 15 extends from a pin 16 on the support 12 to a pin 17 on the bracket 13. The tension of the spring holds the surface of the roll B resiliently against the clamp 14 or bracket 13, and thus holding the end of 75 the paper table-cloth or temporary cover firmly in position. The clamp 14 is preferably formed of spring metal so that it may fit tightly into engagement with the sides of the table. Where the table is especially 80 long, two rollers B¹ and B² may be used, as shown in Fig. 10, placed end to end and connected by a central connecting pin 18 supported from a bracket 19 connected to a clamp 20 which will engage the side of the 85 table.

On the opposite side of the table to that along which the roll B extends, a retaining bar C is provided supported by arms 21 pivoted to brackets 22 connected to spring 90 clamps 23 of similar form to the clamps 14, and which embrace the top board of the table at opposite ends. The retaining bar is adjustable in length, being formed in two sections 24 and 25, each having a series 95 of perforations 26 therein, the perforations on opposite sections being connected by suitable bolts.

At right angles to the retaining bar C, a cut-off bar 27 is provided having a lower 100 cutting edge. It will be seen that, when the table-covers are soiled, a new cover may be drawn from the roll B, and the soiled portion cut off against the bar 27.

Fig. 9 shows an alternative form of 105 spring clamp to be used on tables having rounded edges.

It will be seen that, when the soiled table-covers are cut off by the bar 27, the retaining bar C will engage the under-surface thereof 110 and will press the same against the table by means of springs 28 which extend from pins

29 on the arms 21 to pins 30 on the brackets 22. It will be seen that, in this way, the opposite end of the table-cloth will be held firmly in position.

5. It will be seen further that a new table-cloth may be readily removed from time to time by pulling the same through the desired amount, and then cutting off the soiled portion.

10. As many changes could be made in the above construction and many apparently widely different embodiments of my invention within the scope of the claims, constructed without departing from the spirit 15 or scope thereof, it is intended that all matter contained in the accompanying specification and drawings shall be interpreted as illustrative and not in a limiting sense.

What I claim as my invention is:

20. 1. A device of the character described comprising a roll of covering material, means for supporting the same in position on one side of a table, means for normally preventing turning of the roll, a retaining member adapted to retain one end of the covering material against the opposite side of the table to which the roller is attached, and a cut-off bar on the retaining member.

2. A device of the character described 30 comprising a roller, pivoted supporting members for the roller brackets connected

to the supporting members, spring clamps connected to the brackets, springs extending between the brackets and the supporting members, a retaining bar adapted to extend 35 along the opposite side of the table to that on which the roll extends, pivoted supporting members for the bar, brackets supporting the supporting members, springs between the supporting members and the 40 brackets, and spring clamps adapted to engage the table and connected to the brackets.

3. A device of the character described comprising a roller, pivoted supported members for the roller, brackets connected to 45 the supporting members, spring clamps connected to the brackets, springs extending between the brackets and the supporting members, a retaining bar adapted to extend along the opposite side of the table to that on 50 which the roll extends, pivoted supporting members for the bar, brackets supporting the supporting members, springs between the supporting members and the brackets, spring clamps adapted to engage the table 55 and connected to the brackets, and a cut-off bar on the retaining bar.

In witness whereof I have hereunto set my hand in the presence of a witness.

WALTER DE MATTOS.

Witness:

RUSSELL B. SMART.
